UNITED STATES PATENT OFFICE.

WILLIAM B. CUNNINGHAM AND PHILIP HILL, OF PHILADELPHIA, PA.

DESIGN FOR FRINGE.

Specification forming part of Design No. 5,424, dated December 19, 1871.

To all whom it may concern:

Be it known that we, WILLIAM B. CUNNINGHAM and PHILIP HILL, of the city and county of Philadelphia and State of Pennsylvania, have invented a new and useful Design for Fringe; and we do hereby declare the following to be a clear and exact description of the nature thereof, sufficient to enable others skilled in the art to which our invention appertains to fully understand and use the same, reference being had to the accompanying photographic illustration, which represents the said design, consisting of the fringe portion A and the head of gimp B, formed together during the operation of wearing.

It will be seen that the design is tasty and attractive, and combines utility with ornamentation.

We claim—

The design for fringe with the gimp formed together, as set forth and shown.

To the above we have signed our names this 24th day of June, 1871.

W. B. CUNNINGHAM.
PHILIP HILL.

Witnesses:

JOHN A. WIEDERSHEIM,
PERCY V. KNEASS.
